CIRCUIT BREAKER

Hiller D. Dorfman, Forest Hills, Pa., assignor to
 Westinghouse Electric & Manufacturing Company, East Pittsburgh, Pa., a corporation of Pennsylvania

Application May 15, 1941, Serial No. 393,535

18 Claims. (Cl. 200—116)

This invention relates to circuit breakers and more particularly to circuit breakers of the type which are tripped instantaneously on overload currents above a predetermined value, and after a time delay on overloads below said predetermined value.

One object of the invention is to provide an improved circuit breaker of the above type that is compact, safe and reliable in operation, and which can be manufactured at low cost.

Another object of the invention is to provide a multipole circuit breaker embodying an improved trip mechanism in which the main latch is moved to release the operating mechanism by any one of a plurality of spring biased trip members each restrained in inoperative position in a novel manner by an individual bimetal element.

Another object of the invention is to provide an improved multi-pole circuit breaker having a plurality of trip members biased by springs to trip the breaker, and a plurality of bimetal elements each having a free end disposed in the path of movement of its associated trip member at all times for opposing movement of the trip member to tripping position.

Another object of the invention is to provide a multi-pole circuit breaker having a plurality of tripping elements each independently movable to trip the breaker, an individual means for moving each tripping element to trip the breaker, and a plurality of bimetal elements one for each trip element, each bimetal element being disposed to yieldingly oppose tripping movement of its corresponding trip element through substantially the entire range of tripping movement.

Still another object of the invention is the provision of an improved multi-pole circuit breaker having a trip device comprising a bimetal element and an electromagnetic trip means for each pole, each bimetal element being disposed to yieldingly oppose operation of the corresponding magnetic trip means.

Another object of the invention is to provide a multi-pole circuit breaker having a plurality of independently movable trip members each movable to trip the breaker by an individual overload electromagnet energized by current of its corresponding pole, and a plurality of thermally responsive bimetal elements one for each trip member each yieldingly opposing tripping movement of its corresponding trip member, the construction being such that any one electromagnet when operated has only to overcome the spring force of the corresponding bimetal element to trip the breaker.

A further object of the invention is the provision of a multi-pole circuit breaker having a common operating mechanism and a trip device comprising a plurality of independently movable tripping members one for each pole each biased to move to a tripping position to cause automatic opening of the breaker, and a separate current responsive bimetal element for each pole disposed to yieldingly oppose tripping movement of its corresponding trip member by the inherent resilience of the bimetal element and operable when heated a predetermined amount by overload current to permit movement of its corresponding trip member to tripping position.

Another object of the invention is the provision of a circuit breaker as described in the preceding paragraphs wherein the tripping movement of any one of the trip members is unopposed by the bimetal element of any of the other poles.

Another object of the invention is to provide a multi-pole circuit breaker having a common operating mechanism for the several poles, and a trip device comprising a plurality of independently operable tripping members each operable to cause automatic operation of the breaker and each comprising a series overload electromagnet and a current responsive bimetal element which cooperates in a novel manner with the electromagnet to provide an improved automatic operating characteristic.

Another object of the invention is to provide a multi-pole circuit breaker having a plurality of trip members each of which members is biased to unlatching position and independently movable, each trip member being yieldingly restrained by a thermal element responsive to overload currents of its pole.

The novel features that are considered characteristic of the invention are set forth in particular in the appended claims. The invention itself, however, both as to structure and operation, together with additional objects and advantages thereof, will be best understood from the following detailed description of one embodiment thereof when read in conjunction with the accompanying drawings, in which:

Figure 1 is a top plan view of a three pole circuit breaker embodying the principles of the invention, a portion of the cover being shown broken away to more clearly show the structure.

Fig. 2 is a sectional view of the circuit breaker taken substantially along the line II—II of Fig. 1, the breaker being shown in closed circuit position.

Fig. 3 is a sectional view similar to Fig. 2, but

showing the circuit breaker in the tripped open position.

Fig. 4 is a perspective view of the trip device, and a portion of the circuit breaker operating mechanism, and.

Fig. 5 is a top plan view of the trip bar.

Referring to Figures 1 and 2 of the drawings, the circuit breaker includes a base 11 of molded insulating material on which the several elements of the mechanism are mounted. The circuit breaker comprises three separate poles, each of which is provided with terminals 13 and 15 for connecting said poles in electrical circuits, a stationary contact 17, an arc extinguisher 19, a movable contact 21, and a trip device indicated generally at 23. Each of the movable contacts 21 is mounted on the free end of a resilient contact arm 25 having its other end secured to a frame member 27. A flexible shunt conductor 29 connects the movable contact 21 with a conductor 31 which completes the electrical circuit from the shunt 29 to the trip device 23. A cover 24 of insulating material is provided and forms a part of the closure for the mechanism.

Each of the stationary contacts 17 is secured by means of a screw 33 to the formed over end of a conductor 35 which connects it to the terminal 15. The terminal 13, at the opposite end of the breaker from the terminal 15, is connected by a flexible shunt conductor 37 to a point near the free end of an arcuate shaped thermally responsive element 39 of bimetallic material. The other end of the thermal element 39 is secured to the conductor 31 by a screw 41.

Baffles 16 are moulded integral with the base 11 between the poles, and similar baffles 26 moulded integral with the cover 24 cooperate to form a substantially separate chamber for each pole.

The electrical circuit for each of the poles is essentially the same and extends from the terminal 13 through the flexible shunt 37, the thermal element 39, conductor 31, flexible shunt 29, contacts 21 and 17, and conductor 35 to the terminal 15.

The operating mechanism for the breaker is supported on a U-shaped frame 43 secured to the central portion of the base 11 by means of screws 45. This mechanism includes a forked operating lever 47, toggle links 49 and 51, a pair of overcenter springs 53 and a releasable cradle 55 controlled by the trip device 23. The cradle 55 is pivotally supported on the frame 43 by a pin 56. The operating handle 47 is pivotally supported on the frame 43 by pivot pins 57 and has secured to its outer end an insulating shield 59 for covering an opening 61 in the cover 24, through which opening extends a handle projection 63 of the shield to permit manual operation of the circuit breaker.

The toggle links 49 and 51 are pivotally connected by a knee pin 65. The link 51 is pivotally connected by a pivot pin 67 to the center pole frame member 27 which carries the central contact arm 25, and the link 49 carries a pin 69 which fits in a pivot bearing recess in the apex of the cradle 55 and is retained in the recess by the overcenter springs 53 tensioned between the knee pin 65 and the outer portion of the operating lever 47. The overcenter movement of the toggle 49-51 is limited by a stud 66 on the link 51 just below the knee pin 65 striking a projection 68 on the cradle 55. This projection also acts to positively start the collapse of the toggle when the breaker is tripped automatically in response to an overload as will be described later.

The clockwise and counter-clockwise movements of the handle 47 are limited by offset projections 71 and 73 respectively on the mechanism frame 43. The three contact arm frames 27 are rigidly connected together by an insulating tie bar 75 which is rigidly fastened to each of the frames 27 by a strap 77. The assemblage of the contact arm frames 27 is pivotally mounted on the mechanism frame 43 by means of a single pivot pin 79.

The trip device 23 (Fig. 2), as previously mentioned, includes three arcuate thermally responsive elements 39, there being an element 39 connected in series in the circuit of each pole of the breaker. The trip device also includes a trip bar 81 common to all three poles. The trip bar 81 is of molded insulating material and is pivotally supported by means of an axially disposed rod 83 extending therethrough which is rotatably supported at each end by a pair of spaced brackets 85. These brackets, one being disposed at each end of the trip bar 81, are supported on shoulders 87 molded in the base 11 and are secured to the shoulders by means of screws 89. The trip bar 81 is provided with three arms 91 formed integral therewith and three trip members 93 are disposed one above each of the arms 91. The free ends of the arms 91 carry projections 95 which extend into openings 97 in the trip members 93 to align the members. The right hand ends (Fig. 2) of the trip members are bent as indicated at 99 to engage notches 101 in the body of the trip bar 81. Springs 103 compressed between a cross bar 105 supported on projections 107 of the baffles 16 and the trip members 93, bias said members 93 against the trip bar 81 at one end and bias adjusting screws 109 at the opposite end of the members 93 against the free ends of the thermal element 39. Lock nuts 111 are provided to retain the screws 109 in their adjusted positions. The ends of the springs 103 are seated around a plurality of portions 128 stuck out from the trip members 93, the portions 128 acting as a spring seat.

A U-shaped latch member 113, rigidly molded integral with the trip bar 81 normally engages the latch end of the cradle 55 and thereby restrains the operating mechanism against automatic circuit opening operation.

When any one of the bimetal elements 39 is heated a predetermined amount by overload current, the free end thereof flexes toward its fixed end. The corresponding trip member 93 follows under the influence of the spring 103 rocking the trip arms 91 and the trip bar 81 counter-clockwise as shown in Fig. 3. At this movement of the trip bar 81 the latch 113 releases the cradle 55 permitting the over-center springs 53 to actuate the operating mechanism and open the contacts as will be more fully described later.

The trip members 93 of the unaffected poles remain in normal positions shown in Fig. 2 so that the spring 103 of the overloaded pole only has to overcome the latch friction to trip the breaker and does not have to compress the bimetal elements 39 of the other poles.

The trip device is also operated electromagnetically to instantaneously trip the breaker upon the occurrence of a heavy overload, for instance, 1000% or more of rated current or on short circuits in the circuit through any pole of the breaker. Each pole of the breaker is provided with an electromagnetic trip means com-

prising a U-shaped core 115 of magnetic material and a cooperating armature 123. The core members 115 are secured to the base by screws 117. Yokes 118 of non-magnetic material fit around the three core members 115 and are retained in position by the screws 117. The conductors 31 for the three poles extend through the respective core members 115 but are insulated therefrom by strips of insulating material 121. The conductors 31 carry the entire current flowing through the several poles and serve to energize the core members 115.

The armatures 123 are mounted on the inner ends of rods 125 extending through and guided by openings in the yokes 118. At their outer ends the rods 125 extend through enlarged openings in the corresponding trip arms 81 of the trip bar 81 and also through openings in the trip members 83. Each rod 125 is provided with a nut 127 screwed on the outer end to provide a means whereby the pull of the core members 115 is transmitted to the trip member 83.

A spring 128 surrounding the armature rod 125 associated with the center pole biases the trip arms 81 and the trip bar 81 to latching position. Only one spring 128 is provided and is compressed between the yoke 118 and the trip arm 81 for the center pole. The yoke 118 for the center pole is formed to provide an outwardly extending lip at the opening for the rod 125 and acts as a seat or retainer for the spring 128. The other end of the spring 128 is seated around a sleeve 131 suitably secured in the trip arm 81 for the center pole.

The screws 108 serve as convenient means for adjusting the tripping time of the breaker when tripped by the bimetal elements 39 on overloads up to a predetermined value, approximately 1000% of normal rated current. The springs 103 maintain the screws 108 in contact with the free ends of their respective bimetal elements 39 at all times and the spring 128 biases the arms 81 of the trip bar into contact with the trip members 83. Consequently if the screws 108 are rotated to move them relative to the trip members 83 the result will be a corresponding movement of the trip members 83 and, due to the influence of springs 103 and 128, the trip bar 81 and the latch member 113 will receive a similar movement to adjust the relationship of the latch member 113 with the cradle 55.

On overloads up to approximately 1000% of rated current the spring 103 assisted by the pull of the electromagnet (armature 123) associated with the pole in which the overload occurs has to overcome the force of the spring 128 and the spring force of the bimetal element 39 for that pole only in tripping the breaker. The pull of the electromagnet in the lower range of overload currents is very slight but increases as the magnitude of the overload increases, and becomes considerable in the higher value overloads even below approximately ten times rated current. Thus on lower overloads as the bimetal becomes heated and bends inwardly, it is the spring 103 which provides the force for rocking the trip member 83, trip bar 81 and the latch member 113 to trip the breaker. On higher overloads below the predetermined value, the spring 103 is assisted by the pull of the electromagnet but since the force of the armature is against the bimetal elements 39 until it has become heated, a desirable but shorter time delay is effected.

The forces exerted to trip the breaker are exerted only against the bimetal element 39 asso-

ciated with the particular pole in which the overload occurs since the trip arms 81 and the trip bar 81 are operable independently of the trip members 83 of the other poles.

When a heavy overload above the predetermined value or a short circuit occurs in any one of the poles, the corresponding electromagnetic trip means is strongly energized and attracts its movable armature 123. This movement, through the agency of the rod 125 and the nut 127, rocks the trip member 83 for that particular pole and the trip bar 81 counterclockwise. The force exerted by the electromagnet on such overloads is sufficient to overcome the inherent resiliency of the bimetal element 39 and the spring 128 and to rock the trip bar 81 to trip the cradle 55 substantially instantaneously.

The circuit breaker mechanism is shown in Fig. 2 in the closed circuit position with the trip device in untripped position. When the trip bar 81 is rocked in unlatching direction in response to an overload in the circuit through any one of the poles, the latch member 113 disengages the cradle 55 and permits that member to rotate clockwise about its pivot 56 under the influence of the overcenter springs 53. At the start of this rotation of the cradle 55 the projection 68 engages the stud 66 and starts the toggle 49-51 in a direction to cause collapse thereof. Continued movement of the cradle 55 carries the center line of the toggle link 49 to the right of the line of action of the springs 53 which act to complete the collapse of the toggle. This rocks the frame 27 counter-clockwise and opens the contacts in all of the poles. Automatic opening of the contacts will take place irrespective of the position of the operating lever 47. The operating lever 47 is also automatically moved to an intermediate indicating position as shown in Fig. 3 upon tripping of the circuit breaker.

Following each opening of the circuit due to an operation of the trip device, it is necessary to reset the operating mechanism to an operative condition before the circuit breaker can be reclosed. As the bimetal 39 cools following a tripping operation in response to an overload below a predetermined value it resumes its normal position (Fig. 2) rocking the trip member 83 clockwise against the force of the spring 103. When this occurs the spring 128 also rocks the trip arm 81 and the trip bar 81 in the same direction to the operative position shown in Fig. 2. To reset the mechanism, the lever 47 is rotated from the position in which it appears in Fig. 3 to its extreme counter-clockwise or open position. This movement of the lever 47 is transmitted to the cradle 55 by means of a hook projection 133 which engages a portion 135 of the cradle 55 and rocks the cradle counter-clockwise therewith. As the cradle 55 is rotated the end thereof passes the latch member 113 and engages a pin 137 mounted between a pair of spaced arms 139 formed integral with the trip bar 81. The pin 137 limits the counter-clockwise movement of the cradle 55.

After the cradle 55 has been relatched the contacts may be closed manually by moving the handle 63 clockwise to its closed circuit position. As soon as the line of action of the overcenter springs 53 crosses to the right of the pivot axis 56 of the toggle link 49, said springs cause the toggle 49-51 to move to the overcenter position closing the contacts with a snap action.

In order to open the contacts manually, the operating handle 47 is moved in counter-clock-

wise direction about its pivot 57. This movement carries the line of action of the springs 53 to the left of the pivot axis 69 of toggle link 49 and the force exerted by the springs 53 now biases the toggle 49-51 away from its overcenter position. Before the handle reaches its extreme counter-clockwise position, this force becomes sufficiently great to cause the toggle to collapse. Since the toggle link 51 is pivotally connected to the central contact arm frame member 27, this member is rotated in a counter-clockwise direction about its pivot 79 causing opening of the contacts with a snap action. The contacts are closed manually in the previously described manner.

The circuit breaker is entirely trip free, that is, it operates in response to an overload to open the contacts regardless of the position of the operating lever 47.

The arc extinguishers 19, there being one provided for each pole, are of the spaced plate type and comprise, generally, a stack of slotted plates of magnetic material positioned adjacent the path of movement of the contacts. The presence of these plates causes the arc to move in the direction toward the ends of the slots which results in the breaking up of the arc into a plurality of short arcs and causes cooling and extinguishment of the short arcs.

Having described the preferred embodiment of the invention in accordance with the patent statutes, it is to be understood that various changes and modifications may be made in the particular embodiment disclosed without departing from some of the essential features of the invention. It is, therefore, desired that the invention be interpreted as broadly as possible in view of the prior art, and that it be limited only by what is expressly stated in the following claims.

I claim as my invention:

1. In a multi-pole circuit breaker, the combination with a spring biased actuating member releasable to effect circuit opening operation of the breaker, of a trip device including a trip bar common to all of the poles of the breaker, said bar being biased to latching position, a latch for restraining the actuating member in inoperative position, said latch being operable by the trip bar to unlatch the actuating member, a plurality of trip members operatively associated with the trip bar, said trip members being biased to operate the trip bar, and a plurality of thermal elements each having a free end disposed in the path of movement of a corresponding one of the trip members at all times for opposing movement of said trip member to tripping position, said thermal elements being responsive to predetermined circuit conditions in the circuit of their associated poles to independently cause movement of the trip bar to unlatch the actuating member.

2. In a multi-pole circuit breaker, a plurality of pairs of relatively movable contacts forming a plurality of poles, an operating mechanism for opening and closing the contacts, a latch member operable to cause operation of said mechanism, a trip device including a common trip bar for operating the latch member, said trip bar being biased to latching position, a plurality of independently movable trip members for causing operation of the trip bar, said trip members being biased to tripping position, and a thermal element connected in the circuit of each pole, said elements acting to yieldingly oppose move-

ment of the trip members to tripping position, each thermal element being responsive to predetermined circuit conditions in its corresponding pole to cause tripping movement of its associated trip member independently of the remaining thermal elements, said trip member remaining in engagement with the thermal element during substantially its entire movement.

3. In a multi-pole circuit breaker, a pair of relatively movable contacts for each pole, operating mechanism for substantially simultaneously opening and closing said pairs of contacts, a common trip bar including a latch member, said bar being operable to cause operation of the operating mechanism, a plurality of trip members, one associated with each of a plurality of the poles, said trip members being individually biased to operate the trip bar, a plurality of thermal elements, one operatively associated with each trip member to normally restrain the trip members in inoperative position, said thermal elements being responsive to overload currents below a predetermined value in their respective poles to cause operation of the trip members, and a plurality of electromagnets, one for each of a plurality of the poles, said magnets being responsive to overload currents above a predetermined value in their respective poles to operate the trip members.

4. In a multi-pole circuit breaker, relatively movable contacts for each pole, an operating mechanism for said contacts, a trip bar common to at least two of the poles, said trip bar being operable to cause circuit opening operation of the mechanism, a trip member for each of at least two poles of the breaker operable to operate said trip bar, and a thermal element for each trip member having a free end disposed in the path of movement of its trip member at all times for opposing movement of the trip member to tripping position, said thermal element being responsive to predetermined circuit conditions to cause operation of the trip member.

5. In a circuit breaker, the combination of a spring biased actuating member releasable to effect opening of the circuit, a trip device including a releasable latch means for restraining the actuating member in inoperative position, a pivoted trip bar movable from a normal position to a second position to release the latch means, a trip member movable relative to the trip bar and operable to cause operation of the trip bar, a thermal element yieldingly restraining the trip member in inoperative position, said thermal element being responsive to overload currents below a predetermined value to cause operation of said trip member, and an electromagnet operable to operate the trip member.

6. In a circuit breaker, the combination of a spring biased actuating member releasable to cause opening of the circuit, a trip bar including a latch member for restraining the actuating member in inoperative position, said trip bar being biased to latching position, a thermal element heated in response to the current of the circuit, a trip member having one end engageable with the trip bar, said trip member being biased to move the trip bar to release the actuating member, said thermal element yieldingly opposing movement of the trip member to tripping position at all times and being responsive to predetermined circuit conditions to cause the trip member to operate the trip bar to release the actuating member, and an electromagnet

operable to move the trip member to trip the breaker.

7. In a circuit breaker, the combination of an actuating member releasable to cause circuit opening operation of the breaker, a trip bar including a latch member for restraining the actuating member in inoperative position, a bimetal element in the circuit of the breaker, and a trip member operable to operate the trip bar, said trip member having one end biased against the flat side of the bimetal element adjacent the free end of said element, said bimetal element acting to yieldingly restrain movement of the trip member to tripping position and being responsive to predetermined circuit conditions to cause the trip member to operate the trip bar.

8. In a circuit breaker, relatively movable contacts, operating mechanism therefor, a trip bar operable to cause circuit opening operation of said mechanism, a bimetal element in the circuit of the breaker, a trip member biased to operate the trip bar, one end of said trip member engaging the flat side of the bimetal element adjacent the free end of said element, said bimetal being responsive to overload currents below a predetermined value to cause the trip member to operate the trip bar, an electromagnet having an armature operatively connected to the trip member for operating the trip member, movement of the armature being yieldingly opposed by the bimetal element, said electromagnet being operable to cause the armature to operate the trip member.

9. In a multi-pole circuit breaker, the combination of relatively movable contacts, operating mechanism including a member releasable to cause automatic opening of the contacts, a trip device including a latch member for restraining the releasable member, said trip device being provided with a plurality of arms and having a latching position, a plurality of trip members cooperating with said arms, each trip member being individually movable and biased to operate the trip device, a plurality of bimetal elements, one for each of a plurality of the poles, yieldingly opposing movement of the trip members, said bimetal elements each being responsive to predetermined circuit conditions in its associated pole to cause tripping of the breaker, the trip members remaining in engagement with the bimetal elements during movement to tripped position.

10. In a multipole circuit breaker, the combination of actuating mechanism movable to cause opening of the breaker, a trip bar for effecting movement of the actuating mechanism, said trip bar being provided with a plurality of arms and being biased to a normal position, a plurality of trip members each being individually movable and biased to engage a corresponding arm of the trip bar and to operate the trip bar to a tripped position, a bimetal element associated with each pole for yieldingly restraining its corresponding trip member in inoperative position, and a plurality of electromagnets responsive to overload currents and each having an armature operatively connected to one of the trip members, said bimetal elements yieldingly opposing movement of the armatures and being responsive to overload currents below a predetermined value to cause the trip members to reduce the air gap of the electromagnets and cause tripping of the breaker.

11. In a circuit breaker, the combination of a spring biased actuating means releasable to cause opening of the breaker, a trip device including a latch member for normally restraining the actu-

ating means in inoperative position, a trip bar having a normal position and operable to effect unlatching of the actuating means, a trip member biased to operate the trip bar, electromagnetic means connected to the trip member and responsive to overload currents above a predetermined value to substantially instantaneously operate the trip bar, and a thermal element resiliently restraining the trip member in inoperative position, said thermal element being responsive to overload currents below said predetermined value to permit movement of the trip member to cause reduction of the magnetic air gap of the electromagnet and permit said electromagnet to effect unlatching of the actuating means.

12. In a multi-pole circuit breaker the combination of an operating mechanism releasable to cause simultaneous opening of the circuits of all of the poles of the breaker, a trip bar extending across at least two poles of the breaker, a latch member on said trip bar for releasably restraining the operating mechanism, a plurality of bimetal elements, one for each pole, a plurality of trip members, each being independently movable and biased to operate the trip bar, said trip bar having a plurality of arms engageable by the trip members and opposing unlatching operation of said members, each of the bimetal elements being responsive to overload currents below a predetermined value in the circuit of its associated pole to cause operation of the corresponding trip member independently of the other trip members to unlatch the operating mechanism and an electromagnetic means operatively connected to each trip member and responsive to overload currents above said predetermined value to operate said trip member.

13. A trip device for a multi-pole circuit breaker comprising a trip bar operable to cause opening of the breaker, a plurality of independently movable trip members one for each pole each biased to operate the trip bar, a thermal element for each trip member yieldingly holding the trip member against tripping movement, and an electromagnetic means for each trip member operable to cause tripping movement thereof.

14. A trip device for a multi-pole circuit breaker including releasable operating mechanism for causing simultaneous opening of the circuits of all of the poles, said trip device comprising a latch member for restraining the operating mechanism, said latch member having a latching position and being movable to a tripped position, a plurality of trip members independently operable to cause unlatching of the operating mechanism, individual means for biasing the trip members to unlatching position, a plurality of thermally responsive elements, one for each trip member for yieldingly holding said trip members against movement to tripping position, and a plurality of electromagnets, one for each pole, for operating the trip members in response to predetermined circuit conditions.

15. In a multi-pole circuit breaker, the combination of an operating mechanism for the several poles and a trip device comprising a plurality of individually movable tripping members, each member being movable to a tripping position to cause automatic operation of the breaker, a separate series overload electromagnet for each of a plurality of the poles acting to move the corresponding trip member to tripping position, and a separate current responsive bimetal element for each pole disposed in cantilever manner to yieldingly oppose tripping movement of its

corresponding trip member, each bimetal element being operable in response to predetermined overload conditions to permit tripping operation of its corresponding trip member.

16. In a multi-pole circuit breaker, the combination of an operating mechanism for the several poles, and trip device comprising a plurality of independently movable tripping members biased to move to a tripping position to cause automatic opening of all of the poles of the breaker, and a separate current responsive bimetal element for each of a plurality of poles disposed to yieldingly oppose tripping movement of its corresponding trip member by the inherent resiliency of the bimetal element and operable when heated a predetermined amount by overload current to permit movement of its corresponding trip member to tripping position. 10 15

17. In a multi-pole circuit breaker, the combination of an operating mechanism and a trip bar extending across at least two poles of the breaker and operable to trip the breaker, a plurality of independently movable tripping members each 20

biased to move to tripping position to operate the trip bar to trip the breaker, and a separate current responsive bimetal element for each pole disposed in cantilever manner to yieldingly oppose tripping movement of its corresponding trip member, the tripping movement of any one of the tripping members being unopposed by the bimetal elements of any of the other poles.

18. In a multi-pole circuit breaker, operating mechanism for the several poles, a trip member movable to cause the operating mechanism to open all of the poles, a plurality of bimetallic members, each responsive to the current through one pole and operable to cause actuation of the trip member, a plurality of electromagnets, each responsive to the current through one pole and operable to cause actuation of the trip member, and each of said bimetallic members being connected to one of said electromagnets to vary the tripping point of the electromagnet as the bimetallic member is moved in response to current.

HILLER D. DORFMAN.
